(57) **CLAIM**

The ornamental design for a battery for use in a mobile device, as shown and described.

DESCRIPTION

FIG. 1 is a front perspective view of the invention;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top view of FIG. 1; and,

FIG. 7 is a bottom view of FIG. 1.

Any elements shown in dash-dot broken lines form no part of the claimed invention in this application, and are instead included to show environmental aspects of the claimed invention.
